DESIGN FOR A BUTTER MOLD OR SIMILAR ARTICLE

John L. Wade, Los Angeles, Calif., assignor of
one-third to Ray Swanson, Los Angeles, Calif.,
and one-third to William Wirt Lake, Pasadena,
Calif.

Application January 12, 1943, Serial No. 109,238

Term of patent 3½ years

To all whom it may concern:

Be it known that I, John L. Wade, a citizen of the United States, residing at Los Angeles, in the county of Los Angeles and State of California, have invented a new, original, and ornamental Design for a Butter Mold or Similar Article, of which the following is a specification, reference being had to the accompanying drawing, forming a part thereof.

Fig. 1 is a top perspective view;
Fig. 2 is a bottom perspective view;
Fig. 3 is a side elevational view; and
Fig. 4 is an end elevational view of a butter mold showing my new design.

I claim:

The ornamental design for a butter mold or similar article, as shown.

JOHN L. WADE.
